LOG BARGE

Ludwig S. Baier, Portland, Oreg.

Application April 21, 1952, Serial No. 283,327

9 Claims. (Cl. 114—27)

1

This invention relates to coastal and seagoing transportation of logs, and material having like buoyant characteristics.

It has been customary to employ various equipment in shipping logs, such as rafts, deck barges and the like, but all have been found impractical for various reasons, such as failures of the bindings and lashings in retaining the logs together, especially in bad weather, and due to losses, and increased insurance by the underwriters has restricted the towing of log rafts to a few months of the year. Then again, some barges because of too great a deck load have capsized. In view of these and other conditions, and losses of loads, the cost of such transportation is very high, and with barge loads the capacity must be materially reduced or limited to provide proper stability.

The assembling of a seagoing raft is most costly due to today's high labor costs and the failure of lashings or bindings to properly hold the raft together, especially in heavy weather, has resulted in considerable loss. Furthermore, when a raft breaks up at sea it becomes a menace to navigation as logs four feet and up in diameter and of lengths from thirty to forty feet can cause severe damage to a ship.

In making up a log raft for sea tow, chains and cables are used for bindings. While these are tightened at the time the raft is assembled, it is impossible to get them tight enough to prevent "working" of the mass of logs when in a sea way. Therefore, the raft is not a rigid member. This continual weaving and rolling motion of the sea sets up considerable friction among the logs, and even though they are wetted this friction is sufficient to cause fire. It will be appreciated that it is difficult to tie or bind a large number of logs of various sizes and lengths into an absolutely rigid member whereby this frictional condition between the logs can be eliminated.

It is, therefore, one of the purposes of this invention to overcome these objections, and to provide transportation for greater loads with increased stability.

The invention consists in providing a rigid buoyant center member, to the sides of which, logs or timbers are lashed or secured, which will increase the stability and buoyancy of the center member and at the same time increasing the load carrying capacity of the loading area above the combined center member and side loads. Extending the load laterally beyond the center member makes it possible to maintain a low center of gravity, and eliminates the possibility of capsize.

2

Another feature of the invention is in the provision of a ship or barge which will act and function as a rigid buoyant member, to which a log or timber cargo can be properly secured, and utilizing a part of the load for buoyant purposes by securing it to the sides of the hull, thereby increasing the buoyancy and stability of the ship or barge and the load carrying capacity.

A further feature of the invention is in securing 10 to the rigid buoyant member or steel hull the logs or timbers in such a manner that regardless of weather or conditions of the sea, the cargo will remain intact; and which securing means can be readily manipulated in the discharge of the cargo from the buoyant member or hull.

It is the purpose of this invention to provide 20 a hull, of ship or barge shape, to act as a rigid buoyant member to which a log cargo would be properly secured. The particular design of the hull lines is immaterial so far as this application is concerned as all seagoing hulls must be assigned a load line by the American Bureau of 25 Shipping and outfitted to meet United States Coast Guard Regulations. One particular type of hull suitable for the purpose is ship shaped, and having dimensions of 183 feet, by 33 feet, by 15 feet, and has a safe load capacity of 370,000 board feet of logs. By providing this hull with 30 side cradles or pockets, which will be more specifically set forth hereinafter, it has a safe load capacity of 708,000 board feet. In the event of hull damage the logs in the cradles or pockets would tend to act as outriggers or outboard lifting pontoons.

A hull constructed of steel, which when loaded 35 would permit a greater payload by virtue of the fact that part of the payload is carried in the cradles or side pockets disposed along the sides of the hull, and the remainder or deck load is arranged to project and extend over the side pockets. The logs in the side pockets provide additional buoyancy for the hull and add to the stability of the hull to such an extent that a greater, than ordinary, deck load can be safely transported.

In a normal ship hull loaded either inside or 50 on deck there are limits to what the hull can carry with proper consideration to stability. It should be appreciated, however, that because this invention is directed to the carrying of a cargo consisting of timbers or logs which in themselves are buoyant, and not a dead weight cargo, such as concrete or structural steel, and utilizing part 55 of this load for buoyant purposes, the problem of transporting logs and timber by employing a

rigid buoyant member or steel hull and securing the logs or timbers thereto the cargo will remain in tact as it cannot move or change its position regardless of the weather or conditions of the sea as the cargo is being transported.

In the accompanying drawings:

Figure 1 is a view in side elevation illustrating the load of logs or cargo lashed to the hull of a ship or barge;

Figure 2 is a top plan of the hull of a vessel without its cargo, showing the trip lines for unloading the vessel;

Figure 3 is a detail vertical sectional taken on lines 3—3 of Figure 1;

Figure 4 is a similar view taken along lines 4—4 of Figure 1;

Figure 5 is a view similar to Figure 4, but illustrating the manner of supporting the end chains or lashings during the loading of a pocket;

Figure 6 is a detail view in front elevation showing a chock post in upright position;

Figure 7 is a detail view in side elevation of a chock post attached to a portable skid beam taken on line 7—7 of Figure 6;

Figure 8 is a detail view in section of a portable skid beam attached to the girder;

Figure 9 is a detail horizontal sectional view showing the connection between a skid beam and a portable beam;

Figure 10 is a view in top plan of the operating cable and trip lines attached thereto for releasing the lashings of the cargo, wherein the operating cable is being drawn in the direction indicated by the arrow or toward the bow of the hull;

Figure 11 is a somewhat similar view to illustrate the action on the trip lines when the cable is moved in a direction toward the stern of the hull or in an opposite direction to that shown in Figure 10;

Figure 12 is a detail view in elevation showing the mounting of the sheaves on the deck and about which the trip lines travel;

Figure 13 is a detail sectional view showing a method of attaching trip lines to operating cable;

Figure 14 is a view in detail in perspective showing the outboard girder attached to a side of the hull with the main beams and portable beams supported on the girder; and with lashings and trip lines;

Figure 15 is a transverse vertical sectional view of loaded hull with lashings attached to a central flexible chain or cable, which may be substituted for center posts shown in Figures 1 and 2;

Figure 15a is a detail view in section, showing a trip line passing over a sheave on the deck and extending along side of the hull in a fender or guard;

Figure 15b is a detail view in cross section of the side of the hull and fender or guard, taken along line 15b—15b of Figure 15a;

Figure 16 is a diagrammatic view to illustrate the load or cargo that can be carried on a given hull in accord with the present invention; and

Figure 17 is a similar view illustrating the same size hull with the usual pay load or cargo.

This invention is primarily directed to transportation of logs or timbers and the like, wherein in a log raft or barge having a center buoyant member or hull is employed and on which and to the sides thereof the logs are lashed or bound. The logs or timbers being of a buoyant character when lashed to the sides of the hull afford additional buoyancy to the hull and provide facilities for transporting a greater pay load and at the same time make for a more buoyant raft or

barge having greater stability for safe transportation.

Figures 16 and 17 disclose the loading or cargo of given size hulls, and the difference, based on calculations, between the load that could be carried without the side pocket loadings and the necessary ballast required to give stability, see Figure 17, and the load that can be carried or transported in accordance with the present invention, Figure 16, with increased stability, buoyancy, and carrying capacity, and to maintain a low center of gravity. It will be apparent from the disclosure in Figure 16 that the greater portion of the logs in said pockets will be submerged when the entire deck load is on the vessel or hull. This arrangement will thus add to the buoyancy and also increase the stability of the vessel or hull. It would not be feasible to totally submerge the entire pocket load of logs for the reason that that the vessel would have no freeboard. Again, the degree of submergence of the side pockets of logs would be governed by the payload carried on the deck. By carrying the logs in the side pockets as wing loads the waterline plane is increased thereby increasing the stability of the vessel or hull.

A hull or buoyant member 19, preferably of metal, is constructed in the shape of a ship or barge having the usual bow and stern, and is provided with a deck 11. For the purpose of illustration and for practical purposes the hull may be 183 feet, by 33 feet, by 15 feet, and attached to each side 12 of the hull is an outboard girder 13. The girder is suitably laterally spaced with respect to the side of the hull and is connected at its ends to the sides 12 but intermediate the ends metal gussets 14 are interposed between the sides 12 and the girder and secured to the girder and hull by any suitable means, such as welding. The gussets 14 are arranged in spaced relation to each other and are substantially thirty feet apart. Mounted upon the deck are a plurality of transverse beams 15, preferably I-shaped metal beams, which extend from the center line of the hull in both directions and overlie the gussets 14 and are connected at their outer ends to the girders 13. These transverse beams are preferably welded to the deck and girders, although other fastening means might be employed. Interposed between adjacent transverse beams and mounted on the deck 11 are two skid beams 16 which may be of like construction to the transverse beams or could be otherwise constructed of both metal and wood, or metal faced wood beams, however, in this instance they have been shown as made of metal. The outer ends of these skid beams terminate short of the sides 12. Connected to the outer ends of the skid beams are portable skid beams 17, preferably of I-beam construction. Plates 18 are secured to the web of the skid beams 16 by rivets or welding 19, and the web of the portable skid beams 17 are secured to these plates 18 by means of a bolt 20 to allow for disconnecting the portable skid beams from the skid beams 16. The outer ends of the portable skid beams 17 are supported upon the girders 13. Ears or lugs 22 formed on the girder 13 are disposed on each side of a portable skid beam 17 and a bolt 23 extends through the ears and the portable skid beam for removably holding the portable skid beam on the girder 13.

Secured to the outer ends of the portable skid beams 17 and transverse beams 15 and on each side of the said beams 15 and 17 are plates 24 forming bifurcated ends at the outer ends of these beams. Chock posts 26 are located between plates

24 and are pivotally connected to these plates at their lower ends by pivot pins 27. These posts 26 project upwardly from the girder and their inner surfaces abut against the outer ends of the beams 15 and 17. These posts during the loading of the deck are held in their upright positions by means of latches 28 which are pivotally connected to a plate 24 and received in a recess or slot 29 in the opposite plate 24 so that the posts are held in an upright position. With the beams 15 and 17 secured or connected to the girder 13, the girder is substantially secured to the side of the ship to provide a rigid structure.

Located between the inner ends of the transverse beams 15 and the skid beams 16 are center posts 30. These posts are secured in any suitable manner to the deck 11. Connected to the upper ends of each center post 30 are lashing chains or binders 32. These chains extend over the top of the logs or timbers toward both sides of the hull and are connected to pelican hooks attached to the upper ends of the chock posts 26 by shackles 34. It is well known that the pelican hook consists of a shank 36 and a member 37 hinged thereto, which member is intended to overlie the shank when the pelican hook is in place and a ring 38 carried by the shank 36 is adapted to be swung over the beak or end of the pivoted member 37 for locking the pelican hook members together. For each lashing chain or binder 32 is provided a turn buckle 40 attached to center posts 30, for the purpose of taking up any slack in the chain or binder after it has been connected to its respective chock post 26.

In Figure 15 the deck load is supported in a similar manner to that just described, and as illustrated in the other figures, but in Figure 15 center chains 42 are substituted for the center post 30 and these chains 42 are secured to the deck 11. Two turn buckles 40 are attached to the ends of each chain 42, to which lashing chains 32 are connected.

Cradles or pockets are formed or provided along each side at intervals throughout the length of the hull. These pockets or cradles are provided between the sides 12 and the girder 13 and between the gussets 14 and beams 15. As previously stated the distance between the gussets is approximately thirty feet and by attaching lashing chains 45 to pad eyes 46 on the outer walls of the hull or sides 12 by pelican hooks 36 and then attaching the short lengths of chains 43, which are connected to ring links 44 provided in the lashing chains 45, to pad eyes 47 located on the underside or flange of outboard girder 13, a loading pocket or cradle is provided. As illustrated, there are preferably four lashing chains 45 for each pocket provided between the adjacent gussets, girder 13 and side of hull, however, it is not the intent to be limited to the number of the lashing chains 45 to be employed. The free and remaining portions of the lashing chains may be draped or looped over the girder 13 until the pocket or pockets are filled with the logs or timbers. When a pocket is filled or loaded the draped ends of lashing chains 45 are passed over the logs and shackled to turn buckles 49 attached to pad eyes 48 mounted on the deck 11. The chains 45 are now secured about the logs by adjusting and tightening the turn buckles 49. This causes the short lines 43 to swing upwardly with chains 45 and to slacken off as the chains 45 assume and carry the load of logs. The load imposed on the short chains 43 and girder 13 is now transferred to the chains 45 and pad eyes 48 on the sides of the hull and deck. To load the

pockets, and this is performed before the deck is loaded, the lashing chains 45 are supported by the pad eyes 46 and 47, on the hull sides and girders, respectively, with the ends of the chains 45 draped over the girders 13, to provide or form the pockets, between the sides of the hull and girders. The logs may now be deposited by crane into these pockets or cradles with the longitudinal axis of the logs disposed substantially parallel to the axis of the hull and pocket; after the portable skid beams 17 are removed by disconnecting these beams from the skid beams 16 upon removal of the bolts 28 and the withdrawal of the pins or bolts 23 which attach the portable skid beams 17 to the girder 13. See Figures 7, 8 and 9. After the desired number of logs or timbers are deposited into this space between the ship and girder and principally supported by the end chain lashings 45, the upper portion of all lashings 45 are then attached to turnbuckles 49 which are permanently secured to deck pad eyes 48, and the turnbuckles tightened, thus shortening the lashings 45 and securing the logs or timbers in the several side pockets against movement.

After this operation the portable skid beams 17 are again placed in position whereby they are connected to their respective skid beams 16 and girder 13. The chock posts 26 are now lifted and held by the latches 28 whereupon the deck is loaded and the logs and timbers piled in a pyramid like shape against the chock post 26, so that the logs overlie the pocket logs and girder 13, and with the axis of the logs disposed substantially parallel to the axis of the hull. This method of loading increases the load capacity more than double.

The pelican hooks of the lashing chains 32 and 45 are independently operated for the purpose of unloading the cargo. It will be noted that the pelican hooks each have their hinged end adjacent the chock posts 26 or pad eyes 36 on the hull so that the hinged member of the pelican hook 37 can swing so as to release the lashings from the fastening on the chock posts 26 and pad eyes. Also the latch 28 for each chock post is disengaged from the plates 24 and swung outwardly as indicated in Figure 6 after the logs have been lashed to the deck so that upon the release of pelican hooks of the lashing chains 32 these chock posts will swing outwardly and downwardly as indicated in Figure 7 so that the logs may roll off from the deck on the beams and skid beams. To accomplish this a cable 51 extends lengthwise of the hull through the center thereof and each end is attached to a winch 52 and 53 located on the deck 11. Located on the deck are a plurality of pairs of sheaves 55 disposed on each side of the cable 51. These sheaves are located adjacent the beams 15, 16 and 17. Attached to the cable 51 by means of a coupling 57 are trip lines A and B. Each pair of sheaves 55, is preferably mounted between upper and lower face plates 58, 59 and intermediate face plate 60. These plates are maintained in spaced relation by means of bolts 61 provided with spacers 62. The sheaves are journaled between the plates on a pin 63. The lower face plate 59 is attached to angle iron supports 64, which are attached to deck in any suitable manner. The face plates 58, 59 and 60 prevent the trip lines from becoming fouled and jumping off the sheaves, especially when any of the trip lines are slack.

The trip lines A extend about their respective sheave 55, and along the deck 11 parallel to the

beams 15, 16 and 17, over sheaves 66 mounted on the deck, and which sheaves are provided with face plate 67 to prevent trip lines from becoming disengaged from sheave, see Figure 15a, which is representative of all sheaves for the trip lines. The trip lines A continue over sheaves 68 journaled on pin 21 of the chock posts 26 and then over a sheave 69 on upper portion of chock posts 26 to their respective pelican rings 38.

The trip lines B are conducted similarly to trip lines A, over sheaves 55 and 66 to outer edge of deck 11 and then downwardly along the sides 12 of the hull to pelican hook rings 38 attached to pad eyes 46. Located along the sides 12 of the hull are vertical recessed fenders or guards 70, into the recessed portions of which the trip lines are received, see Figures 15a and 15b. These guards 70 protect the trip lines B from engagement by the logs or timbers in the pockets and becoming jammed or bound and interfere with their free travel and movement. It is to be noted that the trip lines A and B are positioned along the deck and beams so that they will not come in contact with the cargo, but are so arranged that there is nothing to interfere with their free travel and movement.

From Figures 10 and 11 it will be observed that two trip lines A are attached together with the cable 51 at opposite points on the cable from the two trip lines B, and on opposite sides of their respective sheaves 55, so that one set of trip lines A and B lead to one side of the hull and the other set of trip lines A and B to the other side of the hull.

In operating the trip lines the deck load is first released, therefore, the trip lines A will be caused to function upon operating the winch or drum 52. This will put strain on the lines A and slack on the lines B. By placing the pull or strain on the line A the rings 38 of the pelican hooks 26 will be withdrawn from the pivoted member 37 allowing the hooked end to swing outwardly and become disengaged from the chock posts. The chock posts will, due to the action of the cargo, swing outwardly and allow the load to roll from the deck on each side of the hull. Upon operation of the drum or winch 52 trip lines B will be tightened causing the rings of the pelican hooks of the side pockets to disengage the pivoted member of the pelican hooks and allow it to be disengaged from the pad eyes 46 on the sides of the hull. This will release the logs or timbers carried in the side pockets so that they can become detached from the hull.

It is evident from the foregoing that some details of construction are capable of some modifications and substitutions, such as substituting winches for the turnbuckles, and hence it is not the intent to be limited to the exact construction and combinations of parts herein disclosed and described.

I claim:

1. In a log barge assembly, a barge having a deck and sides, means on said deck and extending beyond said sides, a buoyant cargo positioned along said sides in the water and under said means and secured to said deck and said sides thereby affording additional buoyancy to said barge, and a load on said means and deck and extending beyond the sides, said load being supported jointly by said barge and buoyant cargo and augmented by the buoyancy of the cargo with said buoyant cargo substantially in complete submersion.

2. In a log barge assembly, a buoyant hull em-

bodying a deck and sides, outboard means connected to each of said sides and arranged lengthwise and laterally of said sides, flexible means interposed between said sides and said outboard means and connected thereto to provide pockets along said sides, and a plurality of logs received in said pockets and supported by said means with the greater portion of the logs in said pockets being submerged upon the loading of said hull, the logs in said pockets increasing the buoyancy, stability and load capacity of said hull.

3. In a log barge assembly, a buoyant hull comprising a deck and sides, an outboard girder spaced laterally from each side of said hull and extending lengthwise thereof and secured to the sides of said hull, lashings connected to the sides of said hull and to said girders and to said deck for forming pockets along the sides of said hull, logs received in said pockets and supported and secured to said sides by said lashings with the greater portion of the logs in said pockets being submerged upon the loading of said hull, the logs in said pockets increasing the stability, buoyancy and load capacity of said hull, and means on said deck to which said lashings are connected when said pockets are filled to securely bind the logs to the sides of said hull.

4. In a log barge assembly, a buoyant hull comprising a deck and sides, an outboard girder spaced laterally from each side of said hull and extending lengthwise thereof and secured to the sides of said hull, lashings connected to the sides of said hull and to said girders and to said deck for forming pockets along the sides of said hull, logs received in said pockets and supported by said lashings with the greater portion of the logs in said pockets being submerged upon the loading of said hull, the logs in said pockets increasing the stability, buoyancy and load capacity of said hull, means on said deck to which said lashings are connected when said pockets are filled to securely bind the logs to the sides of said hull, beams mounted on said deck and extending over said logs and connected to said girders, additional logs mounted on said deck beams, and means for lashing said last mentioned logs to said beams and deck.

5. In a log barge assembly, a buoyant hull embodying a deck and sides, a plurality of flexible lashings each connected to said deck and to said sides of said hull, buoyant logs disposed between said lashings and sides of said hull and supported by said lashings with the greater portion of said buoyant logs between said lashings and said sides of said hull being submerged upon the loading of said hull, said logs increasing the buoyancy, stability and load capacity of said hull, additional logs mounted on said deck of said hull, and additional lashings connected to said deck for securing said additional logs thereto.

6. In a log barge assembly, a buoyant hull embodying a deck and sides, a plurality of flexible lashings each adjustably connected to said deck and releasably connected to the sides of said hull, buoyant logs disposed between said lashings and the sides of said hull and supported by said lashings with the greater portion of said buoyant logs between said lashings and said sides of said hull being submerged upon the loading of said hull, said logs increasing the buoyancy, stability and load capacity of said hull, additional logs mounted on said deck of said hull, and additional lashings connected to said deck for securing said additional logs thereto, and means for disengaging said lash-

ings from the sides of said hull to release said logs.

7. In a log barge assembly, a buoyant hull embodying a deck and sides, an outboard girder secured to each side of said hull and extending lengthwise thereof, a plurality of lashings each connected to said deck and to the sides of said hull, buoyant logs disposed between said lashings and sides of said hull and supported by said lashings with the greater portion of said buoyant logs between said lashings and said sides of said hull being submerged upon the loading of said hull, said logs increasing the buoyancy, stability and load capacity of said hull, beams mounted on said deck and extending transversely thereof and over said logs and connected to said girders for increasing the deck supporting area, additional logs mounted on said beams, and lashings connected to said deck for securing said additional logs on said deck.

8. In a log barge assembly, a buoyant hull embodying a bow, a stern and deck, an outboard girder spaced laterally from each side of said hull extending lengthwise thereof and secured to the sides thereof, beams mounted on said deck and extending transversely thereof having their outer ends connected to said girders, said beams being arranged at intervals throughout the length of said hull and affording an opening between adjacent beams for the insertion of logs between said girders and said sides of said hull, flexible lashings connected to the sides of said hull and to said girders and disposed along the sides of said hull below said beams for forming pockets along the sides of said hull, logs supported and carried by said lashings along the sides of said hull with the greater portion of the logs in said pockets being submerged upon loading of said hull, the logs in said pockets increasing the stability, buoyancy and load capacity of said hull, removable skid beams disposed between said first mentioned beams and having connection with said deck and said girders, additional logs mounted on said first mentioned beams and skid beams, pivoted chock posts connected to the outer

ends of said beams and skid beams and binding means connected to said chock posts and deck for lashing said additional logs on said beams and deck.

5 9. In a log barge assembly, a buoyant hull embodying a bow, a stern and deck, an outboard girder spaced laterally from each side of said hull and extending lengthwise thereof and secured to the sides thereof, beams mounted on said deck and extending transversely thereof having their outer ends connected to said girders, said beams being arranged at intervals throughout the length of said hull and affording an opening between adjacent beams for the insertion of logs between 10 said girders and said sides of said hull, flexible lashings connected to the sides of said hull and to said girders intermediate said beams for forming pockets along the sides of said hull, a plurality of logs received in said pockets and supported by said lashings with the greater portion of the logs in said pockets being submerged upon the loading of said hull, the logs in said pockets increasing the stability, buoyancy and load capacity of said hull, and removable skid beams 15 disposed between said first mentioned beams and having connection with said deck and said girders for forming a support for the logs carried by said deck and girders.
